TONNEAU COVER FOR DUNE BUGGIES

Henry C. Arnoldy, 30417 J. Carls, and William C. Stanko,
30233 J. Carls, both of Roseville, Mich. 48066

Filed Dec. 3, 1968, Ser. No. 14,760

Term of patent 14 years

Int. Cl. D12—14

U.S. Cl. D14—27

FIG. 3

FIG. 4

FIG. 5

FIG. 6

FIG. 7

FIG. 8

FIGURE 1 is a perspective view of a tonneau cover for dune buggies showing our new design;

FIGURE 2 is a perspective view of a modified form thereof;

FIGURE 3 is a side view of the form shown in FIGURE 1;

FIGURE 4 is a top plan view thereof;

FIGURE 5 is a perspective view of another modified form thereof;

FIGURE 6 is a perspective view of still another modified form thereof;

FIGURE 7 is a side view of the form shown in FIGURE 5; and

FIGURE 8 is a top plan view thereof.

The seat shown in broken lines in FIGURES 3 and 7 is included for illustrative purposes only.

We claim:

The ornamental design for a tonneau cover for dune buggies, substantially as shown and described.
